UNITED STATES PATENT OFFICE.

CHESTER MCNEIL, OF CHICAGO, ILLINOIS, ASSIGNOR TO UNION SPECIAL MACHINE COMPANY, OF CHICAGO, ILLINOIS, A CORPORATION OF ILLINOIS.

RETAINER FOR SEWING-MACHINES.

1,365,003.

Specification of Letters Patent. Patented Jan. 11, 1921.

Application filed January 30, 1917. Serial No. 145,477.

To all whom it may concern:

Be it known that I, CHESTER MCNEIL, a citizen of the United States, residing at Chicago, in the county of Cook, State of Illinois, have invented certain new and useful Improvements in Retainers for Sewing-Machines, of which the following is a description, reference being had to the accompanying drawing and to the figures of reference 10 marked thereon.

The invention relates to new and useful improvements in retainers for sewing machines, and more particularly to a stationary retainer for holding one of the stitching 15 threads in the proper position to insure stitch formation.

Prior to the invention, stationary retainers of the above character have been used, but it has been customary to mount 20 these stationary retainers on the under surface of the throat plate or when a plurality of retainers are used to mount them on a common support.

An object of the present invention is to 25 provide an improved means for supporting such a stationary retainer so that it may be adjusted vertically by adjusting the support which carries the retainer.

A further object of the invention is to 30 provide an adjusting means for a stationary retainer of the above character wherein the adjusting means also serves to hold the retainer in an adjusted position.

A still further object of the invention is to 35 provide a sewing machine having a plurality of needles and co-operative loopers with a retainer for each looper, together with a supporting means for the retainers whereby they may be separately adjusted and also adjusted laterally relative to each other when 40 the gage of the machine is varied.

These and other objects will in part be obvious and will in part be hereinafter more fully disclosed.

45 In the drawings, which show by way of illustration one embodiment of the invention:—

Figure 1 is front view of a portion of a sewing machine having my improvements applied thereto;

Fig. 2 is a view, partly in end elevation and partly in vertical section, substantially on the line of feed;

Fig. 3 is a plan view of a portion of the work support with the throat plate removed 55 and also the cover plate for the retainer support removed;

Fig. 4 is a sectional view on the line 4—4 of Fig. 3;

Fig. 5 is a sectional view on the line 5—5 60 of Fig. 3, showing a portion of the loopers, the feed being omitted; and

Fig. 6 is a view showing more or less diagrammatically, the needles, the retainers, and the loopers with the parts positioned so that 65 the points of the needles are about to enter the thread triangles for the same.

Prior to my invention, it has been a common practice to construct sewing machines having a stitching mechanism wherein the 70 stationary thread retainer cooperates with one of the stitch forming elements. These thread retainers have to be adjusted with a good deal of accuracy in order that they may properly hold the thread to insure 75 stitch formation. The present invention is directed particularly to the means for supporting the thread retainer so that it may be readily adjusted and set so as to properly coöperate with the looper in the holding of 80 these needle thread loops.

The thread retainer is disposed in a line substantially parallel to the line of feed and is mounted on a pivotal support, the pivotal axis of which is substantially horizontal. 85 Means is provided for swinging the support about its pivotal axis and for holding the same in an adjusted position. Thus the retainer may be quickly shifted in a vertical plane by mechanical means which not only 90 affords a very minute and accurate adjustment, but also efficiently holds the retainer in its adjusted position. This support is also capable of being shifted laterally on its pivotal support and thus provides for a lateral adjustment of the retainer which is particularly useful where a plurality of pairs of needles are used and a plurality of retainers. 95 If it is desired to change the gage of the machine, the retainer may be quickly shifted laterally so as to be properly positioned to coöperate with the looper.

Referring more in detail to the drawings:—

I have shown my invention as applied to a 105 sewing machine having a work support 1

- and an overhanging arm 2. A needle bar 3 reciprocates in the overhanging arm and carries two pairs of needles 4—4 and 5—5. Co-operating with the needles 4—4 beneath the 5 work support is a looper 6, while a looper 7 co-operates with the pair of needles 5—5. The loopers 6 and 7 are mounted on a looper carrier 8 which is pivotally supported on a looper rocker 9. The looper rocker is oscillated for giving to the loopers their needle 10 avoiding movement, by suitable means while the looper carrier is swung on its pivotal support by a link 10, which is of the usual character.
- 15 The material is fed across the work support by a feed dog 11 carried by a feed bar 12, which is moved back and forth by suitable means and which is raised and lowered by an eccentric 13 on the main shaft 14.
- 20 The material is held on the work support by a presser foot 15 which is carried by the presser bar 16.

The looper 6 is formed with a notch 6^a, while the looper 7 is formed with a notch 25 7^a. Co-operating with the looper 6 is a thread retainer 17, and co-operating with the looper 7 is a thread retainer 18. The thread retainer 17 is mounted on a retainer support 19, while the thread retainer 18 is mounted 30 on a retainer support 20. The retainers are connected to the retainer supports, and each retainer support has an opening 21 into which the shank of the retainer extends, and a clamping screw 22 clamps the retainer in 35 said retainer support. The retainer supports are grooved to receive the shanks of the retainers so as to prevent lateral displacement thereof.

The retainer supports are mounted on a 40 pivot rod 23 which is carried by a bracket 24 clamped to the under side of the work support 1 by clamping screws 35 and 36. Each retainer support is freely mounted on the rod and is capable of being swung about 45 the pivot rod 23 and also moved laterally on said rod. A set-screw 24^a operates to clamp the retainer to the pivot rod 23. The retainer support extends to the rear of the pivot rod 23, and an adjusting screw 25 is 50 threaded through this rear end of the retainer support. The bracket 24 carries a plate 26 which is formed with a slot 27. The adjusting screw extends through this slot and the head 28 of the adjusting screw 55 rests against the upper face of the plate, while a collar 29 on the adjusting screw engages the lower face of said plate. This construction prevents the adjusting screw from moving endwise relative to the plate, 60 and its threaded connection with the retainer support serves to hold the retainer support in an adjusted position. When this screw 25 is turned, the retainer support will be shifted about its pivotal axis, and this 65 raises and lowers the retainer in a vertical

plane. The retainer is, of course, adjustable longitudinally by loosening the screw 22 and shifting the same, with which it may be clamped in its new position. The entire retainer support is capable of lateral adjustment, which is accomplished by loosening the screw 24^a and shifting the same laterally on the pivot rod 23. The adjusting screw 25 is shifted along the slot 27 with the retainer support.

75 From the above description, it will be apparent that each retainer support is independently adjustable so as to shift the retainer in a vertical plane, and also each retainer support is laterally adjustable so that the retainer may be shifted in a horizontal plane. If the distance between the pairs of needles is varied, when, for example, changing the gage of the machine, the retainer support may be shifted as required to accommodate the new setting of the needles. Then, again, the retainer may be shifted endwise on the retainer support to bring the end thereof nearer to or farther from the path of the needles.

80 The operation of the retainer will be clear from Fig. 6 of the drawings, wherein I have shown diagrammatically the position of the loopers, the needles, and the retainers when the retainers are operating to hold the two 85 needle loops so as to insure that the needles entering their respective thread triangles will pass into the triangle in advance of both needle thread loops. After the needles are well in the thread triangles, then the 90 needle loops are released so as to produce the proper shedding of the needle thread loops from the looper and the drawing up of the threads. It will be apparent that the end 95 of each retainer must be set with great accuracy, and the above adjustment permits this to be accomplished. The support for the retainers and the adjusting screws are covered by a cover plate 1^a, which may be 100 readily withdrawn to give access to the adjusting screws, and when this cover plate is withdrawn, the operator may quickly turn either of the screws for adjusting one retainer or the other as described.

105 It is obvious that minor changes in the details of construction may be made without departing from the spirit of this invention, as set forth in the appended claims.

110 Having thus described the invention, what is claimed as new is:—

115 1. The combination with a work support, a needle, a looper co-operating with the needle, of a stationary thread retainer for one of the stitching threads for positively holding the same to insure stitch formation, a support for said retainer, means for adjustably securing said retainer to said support, and means for shifting the retainer support for adjusting the position of the retainer, said adjusting means being con- 120 125 130

structed so as to hold the retainer in its adjusted position.

2. The combination with a work support, a needle, a looper coöperating with the needle beneath the work support, of a stationary retainer for engaging the needle thread loop on the looper for holding the same at one side of the path of the needle, a support for said retainer, a pivot rod on which the retainer support is mounted so that it may be adjusted about the rod in a vertical plane, and means for holding the retainer support in an adjusted position.

3. The combination of a work support, a needle, a looper movable in a direction at right angles to the line of feed and coöperating with said needle, said looper having a lateral movement relative to the needle, a stationary retainer for engaging the needle thread loop on the looper for holding the same at one side of the path of the needle, a retainer support, a pivot rod on which said retainer support is mounted so that it may be adjusted about the rod in a vertical plane, and means for shifting the retainer support about its pivot rod and for holding said retainer support in an adjusted position.

4. The combination of a work support, a needle, a looper movable in a direction at right angles to the line of feed and coöperating with said needle, said looper having a lateral movement relative to the needle, a stationary retainer for engaging the needle thread loop on the looper for holding the same at one side of the path of the needle, a retainer support for said retainer, a horizontally disposed rod located at right angles to the line of feed on which said retainer support is pivotally mounted, means for securing the retainer to said rod whereby it may be adjusted laterally, and means for clamping said retainer support to said rod.

5. The combination of a work support, a needle, a looper movable in a direction at right angles to the line of feed and coöperating with said needle, said looper having a lateral movement relative to the needle, a stationary retainer for engaging the needle thread loop on the looper for holding the same at one side of the path of the needle, a retainer support for said retainer, a horizontally disposed rod located at right angles to the line of feed on which said retainer support is pivotally mounted, means for securing the retainer to said rod whereby it may be adjusted laterally, means for clamping said retainer support to said rod, and means for adjusting said retainer support angularly about said rod for holding the same in an adjusted position.

6. The combination of a work support, a needle, a looper movable in a direction at right angles to the line of feed and coöperating with said needle, said looper having a lateral movement relative to the needle, a

stationary retainer for engaging the needle thread loop on the looper for holding the same at one side of the path of the needle, a retainer support, means for adjustably holding said retainer on said support whereby said retainer may be moved endwise relative to the support, a pivot rod having a horizontal axis disposed at right angles to the line of feed on which said retainer support is mounted, and means for clamping said retainer support to said rod whereby it may be moved endwise of the rod.

7. The combination of a work support, a needle, a looper movable in a direction at right angles to the line of feed and coöperating with said needle, said looper having a lateral movement relative to the needle, a stationary retainer for engaging the needle thread loop on the looper for holding the same at one side of the path of the needle, a retainer support, means for adjustably holding said retainer on said support whereby said retainer may be moved endwise relative to the support, a pivot rod having a horizontal axis disposed at right angles to the line of feed on which said retainer support is mounted, means for clamping said retainer support to said rod whereby it may be moved endwise of the rod, and means for angularly adjusting said retainer support about said rod and holding said retainer support in an adjusted position.

8. The combination of a work support, stitching mechanism including a needle, and a looper coöperating with the needle beneath the work support, said work support having a recess in front of the needle, a cover plate for closing said recess, a stationary thread retainer coöperating with the looper for holding the needle thread loop back on the looper to insure the entering of the needle into the thread triangle, a support for said stationary thread retainer, and adjusting screws for adjusting said support in a vertical plane for varying the position of the thread retainer, said adjusting screws being located directly underneath said removable plate whereby they may be readily accessible for adjusting the retainer.

9. The combination with a work support, a needle, a looper coöperating with the needle beneath the work support, a thread retainer coöperating with the looper for holding the needle thread loop back on the looper, a stationary support for the retainer, said retainer support being grooved to receive the shank of the retainer to prevent lateral displacement thereof, means for clamping the retainer on the support, and means for shifting the support for raising and lowering the retainer.

10. The combination with a work support, a needle, a looper coöperating with the needle beneath the work support, a thread

retainer coöperating with the looper for holding the needle loop back on the looper, a support for the retainer, means for adjustably connecting said retainer to said support whereby it may be shifted endwise on said support, means for adjustably supporting and shifting said retainer support

whereby the same may be moved so as to raise and lower the retainer.

In testimony whereof, I affix my signature, 10
in the presence of a witness.

CHESTER McNEIL.
